US0D1110371S

(12) **United States Design Patent** (10) **Patent No.:** **US D1,110,371 S**
(45) **Date of Patent:** **** Jan. 27, 2026**

(54) **ROBOTIC LAWN MOWER**

(71) Applicant: **Nanjing Chervon Industry Co., Ltd.**, Nanjing (CN)

(72) Inventor: **Jiachao Deng**, Nanjing (CN)

(73) Assignee: **Nanjing Chervon Industry Co., Ltd.**, Nanjing (CN)

(**) Term: **15 Years**

(21) Appl. No.: **29/907,307**

(22) Filed: **Jan. 5, 2024**

(30) **Foreign Application Priority Data**

Jul. 5, 2023 (CN) 202330417189.4

(51) **LOC (15) Cl.** **15-03**

(57) **CLAIM**

The ornamental design for a robotic lawn mower as shown and described.

DESCRIPTION

FIG. 1 is a perspective view of a robotic lawn mower showing my new design;

FIG. 2 is a right side elevational view thereof;

FIG. 3 is a left side elevational view thereof;

FIG. 4 is a front elevational view thereof;

FIG. 5 is a rear elevational view thereof; and,

FIG. 6 is a top plan view thereof.

The broken lines in the drawings illustrate portions of the robotic lawn mower that form no part of the claimed design.
